SLICE FOR PAPER MAKING MACHINES

William B. Clements, Kalamazoo, Mich., assignor
to Bryant Paper Company, Kalamazoo, Mich.

Application May 27, 1933, Serial No. 673,196

14 Claims. (Cl. 92—44)

The objects of the invention are:

First, to provide an easily and completely adjustable slice for paper making machines of the Fourdrinier type in which there is a head box and 5 wire for formation of the paper.

Second, to provide such a slice that may be easily adjusted during operation of the machine.

Third, to provide such a slice in which small 10 fibers of the paper stock do not collect as the stock flows to the wire, thus eliminating the formation of ripples and lumps in the completed sheet of paper.

Fourth, to provide such a slice in which it is possible to adjust the flow of stock to the wire so 15 that it is even at all times and eliminates any ripples or unevenness in the final sheet caused by eddies as the stock flows onto the wire.

Fifth, to provide such a slice in which a roll 20 with an expandable surface is used in place of a wall, which is the ordinary practice in slice construction.

Sixth, to provide a slice construction in which 25 there is a dam and means for adjusting the position of the roll relative to the dam to regulate the amount of stock flowing from the headbox to the wire.

Other objects and advantages pertaining to details of construction and operation of my invention will definitely appear from the description 30 to follow. The invention is pointed out in the claims.

A structure embodying the features of my invention is clearly illustrated in the accompanying drawings, in which:

Fig. 1 is a plan view of my improved slice construction with the central portion cut away.

Fig. 2 is an end elevation view of my device taken on line 2—2 of Fig. 1.

Fig. 3 is a vertical sectional view through my 40 apparatus taken on line 3—3 of Fig. 1.

Fig. 4 is a detail vertical sectional view of one end of the roll taken on the line 4—4 of Fig. 1.

Fig. 5 is a detail sectional view of the roll with portions cut away.

Fig. 6 is a detail view of one of the expansion hubs used in adjustment taken on line 6—6 of Figs. 5, 7 and 8.

Fig. 7 is a detail sectional view through one of the expansion hubs taken on line 7—7 of Fig. 3.

Fig. 8 is a detail view of a portion of one of the expansion hubs showing in detail one of the rim sections.

The parts will be identified by their numerals of reference which are the same in all the views.

My device is a slice construction for paper

making machines and is positioned as is usual in slice construction. It controls the flow of paper stock, here shown as 1, from the head box 2 of the machine to the wire 3 on which the paper is formed. The wire is here shown, see Fig. 3, 60 passing over a breast roll 4 and over tube or table rolls 5. In place of the usual gate of a slice, I provide a roll 6 which has a surface that may be expanded or contracted at different points independently of the rest of the surface. 65

The roll 6 comprises a brass tube 7 molded on heads 8 having trunnions 9 and held together by through rods 10 having bolts 11 holding the heads in the ends of the tube. The tube 7 is longitudinally slotted as at 12, the slots extending substantially the length of the tube but ending as at 13 a slight distance from the end of the tube. The tube is preferably of brass but may be of any suitable material. The slots 12 form longitudinal sections 14. 75

A rubber surface 15 is disposed around the tube. This rubber is blown on in the manner usually employed in coating rolls in paper mills and is vulcanized adjacent the ends of the roll but left free at the middle to slide as the brass tube 7 80 is expanded or contracted. Variations of the application of the covering may be made without departing from the invention.

At spaced intervals within the tube 7 are expansion hubs 16. Each hub comprises a plurality of rim sections 17, each of which is screw-threaded as at 18 to receive a screw 19. The screws 19 are radially arranged about the hub, each having thereon a beveled pinion 20. The screws are mounted for rotation in an opening 21 85 in the hub.

The rim sections 17 are provided with extensions 22 extending into grooves 23 in the hub to guide the inward or outward movement of the rim sections as the screws 19 are rotated. The 90 rim sections 17 of each hub 16 are equal in number to the longitudinal sections 14 of the tube 7 and each rim section 17 is attached to a longitudinal section 14 by means of screws or the like extending through the holes 24 in said rim 100 sections.

A plurality of sleeves 25, 26, 27, 28 and 29 are provided extending into the tube 7 through one of the heads 8. The sleeves are concentrically arranged and each is adapted to be rotated independently of the other. Each sleeve extends to a different expansion hub and each sleeve has at its respective hub a gear 30 affixed thereto with a setscrew 31 or in any other manner. The gear 30 is in engagement with all of the 110

pinions 20 in its respective expansion hub so that rotation of the gear 30 rotates the pinions 20 to rotate the screws 19 and thereby expand or contract the hub with the attached tube 7. 5 This provides means for independently expanding one section of the surface of the roller 6 without expanding any other portion.

The trunnions 9 extend into bearings 32 which are mounted in brackets 33 here shown as attached to the head box 2. These brackets have thereon deckle guides 34 which guide the deckle 35 so that it will travel along the wire. The bearings 32 are mounted in a slide 36 which has a screw 37 with a hand wheel 38 connected to 15 move the slide vertically. The slide 36 is mounted in a slide 39 which has a screw 40 with hand wheel 41 for imparting horizontal movement to the end of the roll.

On the same side of the roll 6 as is the head 20 box 2 I provide a dam 42 which is located adjacent the roll 6 and has a cylindrical surface 43 opposed to the surface of the roll 6. The means for moving the roll horizontally thus make it possible to move the roll 6 to or away from the surface 43 to enlarge or decrease the passage 44 between the roll and the dam to control the flow of stock therebetween.

The roll is driven by means of a sprocket or pulley 45 and a chain or belt 46 which leads to any source of power, such as a motor. The motor is not shown here as it is conventional only.

Hand wheels 47, 48, 49, 50 and 51 are provided adjacent the end of the roll. These wheels are respectively attached to the sleeves 25, 26, 27, 28 and 29 and are connected thereto so that the rotation of each wheel will rotate its respective sleeve and will expand or contract one of the expansion tubes.

The operation of the apparatus is as follows: The stock 1 in the head box flows over the dam 42 and through the passage 44 to the wire 3 of the paper making machine. If the stock is a free stock the roll 6 is moved into proximity to the tank 2 so that less of the water will run out of the stock as it passes to the wire. If a slow stock is used the roll 6 is moved further to the left as shown in Fig. 3 so that more water will run out of the stock before the formation of the sheet starts.

It will be seen that adjustment vertically by means of screw 37 will determine the height of the ends of the roll 6 from the wire 3. The distance between the surface of the roll 6 and the wire at intermediate points is adjusted by expanding or contracting the expansion hubs 16.

As the stock 1 is fed to the machine the roll 6 is rotated in a clockwise direction shown in Fig. 3 and the stock flows evenly to the wire. The distance from the surface of the roll to the wire has been adjusted throughout the length of the roll and the roll turns slowly. In this way no pieces of fiber can lodge on the roll to cause a ripple that extends the length of the sheet or which causes a lump when the stock is finally released from the gate of the slice in ordinary practice. The stock flows evenly and I have observed that in using an ordinary slice there is a possibility for eddy currents set up in the head box to cause a ripple in the stock which shows up in the final paper. By means of my adjustable roll I can eliminate any such eddying by varying the size of the opening through which the stock flows to the wire.

The use of the dam 42 is tantamount to the use of two slices, the opening 44 being adjustable

as by one slice and the opening between the roll 6 and the wire 3 being adjustable as by a second slice.

I have described the invention in the form preferred by me, but desire to claim the same broadly as well as specifically, as pointed out in the appended claims.

Having thus described my invention what I claim as new and desire to secure by Letters Patent is:

1. In a slice for a paper making machine, the combination of a tubular roll slotted longitudinally to provide an expansion surface comprising a plurality of longitudinal sections, a rubber cover on said roll, a plurality of expansion hubs spaced from each other and in said roll, each hub comprising a plurality of circumferentially arranged rim sections each secured to one of said longitudinal sections, a plurality of radially arranged screws in each hub, each screw engaging a threaded opening in one of said rim sections and having a pinion thereon, a plurality of concentrically arranged sleeves extending into said roll, each having thereon a gear engaging the pinions of one expansion hub, means on each sleeve for rotating it independently of the other sleeves, end bearings on which said roll is mounted for rotation, vertical and horizontal adjusting means for said bearings, and means for rotating said roll.

2. In a slice for a paper making machine, the combination of a tubular roll slotted longitudinally to provide an expansion surface comprising a plurality of longitudinal sections, a rubber cover on said roll, a plurality of expansion hubs spaced from each other and in said roll, each hub comprising a plurality of circumferentially arranged rim sections each secured to one of said longitudinal sections, means for expanding and contracting said hubs independently of each other, end bearings on which said roll is mounted for rotation, vertical and horizontal adjusting means for said bearings, and means for rotating said roll.

3. In a slice for a paper making machine, the combination of a tubular roll having an expansion surface, a plurality of expansion hubs spaced from each other and in said roll, means for expanding and contracting said hubs independently of each other, end bearings on which said roll is mounted for rotation, vertical and horizontal adjusting means for said bearings, and means for rotating said roll.

4. In a slice for a paper making machine, the combination of a tubular roll slotted longitudinally to provide an expansion surface comprising a plurality of longitudinal sections, a rubber cover on said roll, a plurality of expansion hubs spaced from each other and in said roll, each hub comprising a plurality of circumferentially arranged rim sections each secured to one of said longitudinal sections, a plurality of radially arranged screws in each hub, each screw engaging a threaded opening in one of said rim sections and having a pinion thereon, a plurality of concentrically arranged sleeves extending into said roll, each having thereon a gear engaging the pinions of one expansion hub, means on each sleeve for rotating it independently of the other sleeves, and means for rotating said roll.

5. In a slice for a paper making machine, the combination of a tubular roll slotted longitudinally to provide an expansion surface comprising a plurality of longitudinal sections, a rubber cover on said roll, a plurality of expansion hubs spaced

- from each other and in said roll, each hub comprising a plurality of circumferentially arranged rim sections each secured to one of said longitudinal sections, means for expanding and contracting said hub independently of each other, and means for rotating said roll. 5
6. In a paper making machine, the combination of a head box, a wire for the formation of paper, a slice comprising a cylindrical roll having an expansible surface, means for expanding and contracting portions of said surface independently of other portions of said surface, means for vertically and horizontally adjusting the position of the ends of said roll, means for driving said roll, a dam positioned adjacent said roll and on the same side of said roll as said head box, said dam having a cylindrical surface opposed to said roll. 10
- 15
7. In a paper making machine, the combination of a head box, a wire for the formation of paper, a slice comprising a cylindrical roll having an expansible surface, means for expanding and contracting portions of said surface independently of other portions of said surface, means for vertically and horizontally adjusting the position of the ends of said roll, means for driving said roll, and a dam positioned adjacent said roll and on the same side of said roll as said head box. 20
- 25
8. In a paper making machine, the combination of a head box, a wire for the formation of paper, a slice comprising a cylindrical roll having an expansible surface, means for expanding and contracting portions of said surface independently of other portions of said surface, means for driving said roll, a dam positioned adjacent said roll and on the same side of said roll as said head box, said dam having a cylindrical surface opposed to said roll, and means for moving said roll to or away from said dam. 30
- 35
9. In a paper making machine, the combination of a head box, a wire for the formation of paper, a slice comprising a cylindrical roll hav-
- ing an expansible surface, means for expanding and contracting portions of said surface independently of other portions of said surface, means for driving said roll and on the same side of said roll as said head box, and means for moving said roll to or away from said dam. 40

- ing an expansible surface, means for expanding and contracting portions of said surface independently of other portions of said surface, means for driving said roll, a dam positioned adjacent said roll and on the same side of said roll as said head box, and means for moving said roll to or away from said dam. 80
10. In a paper making machine, the combination of a head box, a wire for the formation of paper, a slice comprising a cylindrical roll, means for driving said roll, a dam positioned adjacent said roll and on the said side of said roll as said head box, said dam having a cylindrical surface opposed to said roll, and means for moving said roll to or away from said dam. 85
11. In a paper making machine, the combination of a head box, a wire for the formation of paper, a slice comprising a cylindrical roll, means for driving said roll, a dam positioned adjacent said roll and on the same side of said roll as said head box, and means for moving said roll to or away from said dam. 90
12. In a slice for a paper making machine, the combination of a cylindrical roll having an expansible surface, means for expanding and contracting portions of said surface independently of other portions of said surface, means for adjusting the position of the ends of said roll, and means for driving said roll. 100
13. In a slice for a paper making machine, the combination of a cylindrical roll having an expansible surface, means for expanding and contracting a portion of said surface independently of other portions of said surface, and means for driving said roll. 105
14. In a slice for a paper making machine having a wire, the combination of a roll, and means for adjusting the clearance between portions of the surface of the roll and the wire independently of the clearance between other portions of the surface and said wire. 115

WILLIAM B. CLEMENTS.
